United States Patent Office

Des. 222,490

Patented Oct. 26, 1971

222,490

PLAYING CARD

St. Barth Alaska, 3811 S. Scoville Ave.,
Berwyn, Ill. 60402

Filed May 1, 1970, Ser. No. 22,777

Term of patent 14 years

Int. Cl. D21—01

U.S. Cl. D34—13

FIG. 2

FIG. 3

FIG. 1 is a perspective view of the fact of a playing card showing my new design;

FIG. 2 is a side sectional view of the card; and

FIG. 3 is a perspective view of the back thereof.

The characteristic feature of my design resides in a playing card having a transparent upper half and an opaque lower half in combination with two separate card indicia on each half of the face of said card.

I claim:

The ornamental design for a playing card, as shown and described.
